UNITED STATES PATENT OFFICE.

JOSEPH H. HEDMARK, OF CHICAGO, ILLINOIS.

DESIGN FOR A VALVE-BODY.

45,994.

Specification for Design.

Patented June 23, 1914.

Application filed March 16, 1914. Serial No. 825,184. Term of patent 14 years.

To all whom it may concern:

Be it known that I, JOSEPH H. HEDMARK, a citizen of the United States, residing at Chicago, in the county of Cook and State of Illinois, have invented a new, original, and ornamental Design for Valve-Bodies, of which the following is a specification, reference being had to the accompanying drawing, forming part thereof.

The figure shown in this drawing is a side

elevation of a valve body, showing my new design.

I claim:

The ornamental design for a valve body, as shown.

JOSEPH H. HEDMARK.

Witnesses:

CECIL E. BRYAN.
E. V. GUSTAFSON.
